UNITED STATES PATENT OFFICE.

HERBERT P. BEERS, OF CHICAGO, ILLINOIS.

COLLAPSIBLE BAG OR SACK.

1,303,757.

Specification of Letters Patent. Patented May 13, 1919.

Application filed August 5, 1918. Serial No. 248,290.

To all whom it may concern:

Be it known that I, HERBERT P. BEERS, a citizen of the United States, residing at Chicago, in the county of Cook and State 5 of Illinois, have invented a certain new and useful Improvement in Collapsible Bags or Sacks, of which the following is a full, clear, concise, and exact description, reference being had to the accompanying drawings, 10 forming a part of this specification.

My invention relates to collapsible bags or sacks.

The principal object of the invention is to provide a practical, simple, effective and 15 protective construction of collapsible bag or sack.

A further object of the invention is to secure strength and lightness and to permit the bag to be quickly and easily filled and 20 emptied and opened and closed, and also to be self-standing.

In the accompanying drawings Figure 1 is a vertical section of a collapsible bag or sack embodying my invention;

25 Fig. 2 is an outside view of a corner of the same;

Fig. 3 is a cross section of said corner on an enlarged scale;

Fig. 4 is a top plan of said bag or sack; 30 and

Fig. 5 is a sectional view of the same in a collapsed condition.

In the drawings I show a bag or sack made of some flexible material, as for example, heavy canvas or leather, of sufficient strength to stand the strain of transportation, and also flexible enough to permit the bag or sack to be collapsed. The bag or sack shown is the usual bag or sack shape, that 35 is when opened a general rectangular shape of any desired height and about the same crosswise dimensions. It is more or less rounded or bulging as shown in Fig. 4. The invention can be applied to bags or sacks of 40 different sizes and shapes.

The bag or sack shown has sides 1, 2, 3 and 4, a top 5, and a bottom 6. Slats are arranged in the sides 1, 2, 3 and 4. In Fig. 1 I show slats 7 and 8 in the sides 3 and 4, 45 respectively, these slats being preferably made of wood or other strong material and held in position by being inclosed in suitable slips or cavities formed by the outer wall or layer of flexible material, and inner layers 9 and 10 secured to said outer walls or layers by rivets 11-11. There may

be different numbers of such slats or reinforcing members as desired. I have shown four in each of the four long sides, 1, 2, 3 and 4. These strips may be easily inserted 60 and withdrawn and replaced. They protect the contents of the bag or sack, and at the same time permit its collapse.

The bottom or end 6 which is also preferably made of a flexible material, such as 65 canvas or leather, or the like, is secured to the sides by means of the rivets 11 and heavy leather strips 12 and corner pieces 13. A supplemental end or bottom 14 is arranged to fit against the inside of the end or bottom 6. This end or bottom 14 is also preferably made of flexible material and is provided with a series of slats 15 whereby said member 14 furnishes strength and reinforcement 70 for the end or bottom. This supplemental end or bottom 14 is attached at one side or edge, as at 16, by a hinged connection formed by the flexible material, to the main body of the trunk, so that said end or bottom 14 can be swung about such pivotal connection 75 16 so as to bring it up parallel and substantially in contact with the side 4. A strip or piece 17 of material is attached to the other side or edge of the bottom 14 and also attached to the side of the bag or sack at 18, 80 by means of rivets or washers 19, whereby the strip 17 serves as a connection with the supplemental end or bottom 14, holding the latter against the outward strains of the material inside the bag or sack when the same 85 is filled. This strip 17 also permits the bottom or end 14 to be swung upwardly against the side 4.

The top of the bag or sack is made open 90 so that the goods to be transported by the bag or sack may be inserted into and withdrawn from said open end. A closure in the form of a swinging member 20 is provided for opening and closing said top. This closure has one edge pivoted as at 20^a and 95 the other end free to swing so as to permit the closure to swing downwardly against the side 4. This closure 20 is also preferably provided with slats 21 arranged in recesses or pockets in the flexible material. The 100 flexible material is extended inwardly to some extent so as to form a curtain or partial covering over the closure 20, as shown in Fig. 5, and a flexible connector such as a rope or cord 22 is provided and passed 105 through eyelets or apertures 23 in the inwardly extending edges 5^a. Thus the bag 110

or sack may be closed by the closure 20 and sealed by drawing the rope 22 tight and then tying its ends together at 24, (Fig. 4). The bag may stand upright on its bottom as shown in Fig. 1.

In Fig. 5 I show the bag or sack in a collapsed condition. The closure 20 is swung against the side 4 and the supplemental bottom or end 14 is also swung upwardly so as 10 to lie lengthwise of the side 4, more or less against the closure 20. The flexible connecting strip 17 is doubled back underneath the bottom or end 14 and the bottom or end 6 is collapsed or bowed inwardly. In this condition it will be seen that the bag or sack 15 occupies a very small space,—only a small fraction of the total space occupied by it when in its expanded condition, as shown in Fig. 1. Furthermore, it can be easily handled, either when full or empty.

It will be seen that the bag or sack can be readily filled and then secured in a filled and closed condition, being sufficiently strong to prevent any bulging or breaking. It will 25 also be seen that it can be readily opened and emptied and then put into a collapsed condition in which it can be readily stored and transported, occupying only a small fraction of the space it occupies when full.

30 The bag can be of other shapes and other changes and modifications may be made without departing from the spirit of the invention.

What I claim is:

35 1. A collapsible bag or sack comprising a casing formed of flexible material provided with reinforcing members, said sides being extended toward one another at the top of the bag or sack, but not meeting one another, 40 whereby an opening is formed, and a top hinged to the inside of the bag or casing and arranged to swing into position to open or close said opening, said top being also made of flexible material and provided with 45 reinforcing strips.

2. A collapsible bag or sack comprising sides made of flexible material and provided with longitudinally extending reinforcing strips and top and bottom members hinged 50 at one edge to the inside of said bag or sack and arranged to swing into position either crosswise of said sides or substantially parallel with the same so as to permit said top and bottom members to be folded inwardly 55 and the sides then to be collapsed upon the same.

3. A collapsible bag or sack comprising sides made of flexible material provided with longitudinally extending reinforcing 60 members, an end or bottom connecting said sides and made of flexible material, a supplemental end or bottom having reinforcing strips, said supplemental end or bottom being connected with the interior of the bag 65 or sack so as to permit it to be swung into a

position lengthwise of one of the other walls of the device, the other end or top having a filling and unfilling opening and closure therefor.

4. A collapsible bag or sack comprising 70 sides made of flexible material provided with longitudinally extending reinforcing members, an end or bottom connecting said sides and made of flexible material, a supplemental end or bottom having reinforcing strips, 75 said supplemental end or bottom being connected with the interior of the bag or sack so as to permit it to be swung into a position lengthwise of one of the other walls of the same, the other end or top having a filling and unfilling opening and closure therefor, said closure being connected so as to permit it to be moved into position lengthwise of one of the other walls of the device. 80

5. A collapsible bag or sack comprising 85 sides made of flexible material provided with longitudinally extending reinforcing members, an end or bottom connecting said sides and made of flexible material, a supplemental end or bottom arranged inside of 90 said end or bottom and having a hinged connection with one side wall of the device whereby said end may be swung upwardly into position lengthwise and close to said side wall, said supplemental end or bottom being connected with the side wall of the device by means of a flexible strip serving to hold said end against outward movement and also permitting the same to swing upwardly to the top of the device, the other end or top of the device having a filling and emptying opening formed by extending the flexible material of the sides and bending the same inwardly, a flexible connector connecting said inwardly extending end portions, and a closure for said opening, said closure being hinged to one side wall of the device and arranged to swing downwardly so as to permit the opening and closing of 95 said aperture. 100

6. A collapsible bag or sack comprising 105 sides made of flexible material and provided with longitudinally extending reinforcing members, an end or bottom connecting said sides and also made of flexible material, a supplemental end or bottom arranged inside of said end or bottom member and having a hinged connection with one side of the bag or sack whereby said end or bottom may be swung upwardly into 110 position lengthwise and close to said side wall, said supplemental end or bottom being connected with the bottom of the device by means of a flexible strip serving to hold said end or bottom against outward movement and also permitting the same to swing upwardly to the side of the device, the other end or top of the bag or sack having a filling and emptying opening formed by extending the flexible material of the sides and bending 115 the same. 120

125

130

- ing the same inwardly, a flexible connector connecting said inwardly extending end portions, and a closure for said opening, said closure being hinged to one side wall of the 45
5 device and arranged to swing downwardly so as to permit the opening and closing of said aperture, said supplemental end or bottom and said closure being made of flexible material provided with reinforcing strips.
- 10 7. A device of the class specified having a bottom made of flexible material, and a supplemental bottom member provided with reinforcing devices and having a hinged connection with the device to permit said 50
15 supplemental bottom member to be swung into position lengthwise of one of the sides of the device to permit the collapse of the flexible bottom.
8. A device of the class specified comprising sides provided with reinforcing members and a top and bottom made flexible to permit collapse, and a supplemental bottom and a supplemental top, each of which is provided with reinforcing members to protect 55
25 the contents of the device and also to prevent collapse when the device is filled, said supplemental top and bottom members having hinged connections with the side walls of the device to permit the same to be swung
30 into position lengthwise of the sides of the device to permit complete collapse of the same.
9. A collapsible bag or sack comprising sides made of flexible material and provided 60
35 with longitudinally extending reinforcing strips and top and bottom members hinged at one edge to the inside of said bag or sack and arranged to swing into position either crosswise of said sides or substantially parallel with the same so as to permit said top and bottom members to be folded inwardly and the sides then to be collapsed upon the same, 65
55 said top and bottom members being made of flexible material provided with reinforcing strips, and the ends of the sides adjacent said top member being extended inwardly toward one another to form a contracted 70
60 opening which is opened and closed by said swinging top member.
11. A collapsible bag or sack comprising four side members made of flexible material and each provided with longitudinally extending reinforcing strips, top and bottom members extended crosswise of said sides and of the reinforcing strips thereof substantially at the ends of the latter, said top and bottom members being hinged at one edge 75
70 to the inside of the sack or bag and arranged to swing into position crosswise of said sides to substantially parallel of the same, said top and bottom members having a reinforcing construction enabling them to hold said 75
80 sides in separated and expanded condition when said members are in their crosswise position.

In witness whereof I hereunto subscribe my name this 30th day of July A. D., 1918. 80
